Primary Examiner — Melody N Brown(74) Attorney, Agent, or Firm — Wolf, Greenfield & Sacks, P.C.(57) CLAIM

The ornamental design for a car, as shown and described.

DESCRIPTION

FIG. 1 is a top, front, right side perspective view of a car showing our new design;

FIG. 2 is a top, rear, left side perspective view thereof;

FIG. 3 is a right side elevation view thereof;

FIG. 4 is a left side elevation view thereof;

FIG. 5 is a front elevation view thereof;

FIG. 6 is a rear elevation view thereof; and,

FIG. 7 is a top plan view thereof.

The dot-dash broken lines in the figures illustrate boundaries of the claimed design and form no part thereof. The dash-dash broken lines illustrate portions of the car that form no part of the claimed design.
